UNITED STATES PATENT OFFICE.

NICHOLAS SIMON, OF NEENAH, WISCONSIN.

DESIGN FOR A CHEESE.

SPECIFICATION forming part of Design No. 34,519, dated May 14, 1901.

Application filed March 11, 1901. Serial No. 50,762. Term of patent 7 years.

To all whom it may concern:

Be it known that I, NICHOLAS SIMON, a citizen of the United States, residing at Neenah, in the county of Winnebago and State of Wisconsin, have invented and produced a new and original Design for a Cheese, of which the following is a specification, reference being had to the accompanying drawings, forming part thereof.

10 Figure 1 is a perspective view of the upper or top side of the cheese and two of its edges, showing my design. Fig. 2 is a perspective view of the reverse or bottom side and the other two edges, and Fig. 3 is a vertical section taken on the line *a a* of Fig. 1.

As shown in the drawings, the leading feature of my design consists of a square cheese having a series of V-shaped grooves A, which divide the cheese into small rectangular sections, twelve of the sections having their greatest length in one direction, four of said twelve being at the corners of the cheese, and six sections, or one-third of the whole number, having their greatest length at right angles with the aforesaid twelve sections and dividing the aforesaid twelve into two equal parts, and thereby forming three groups, in which all of the sections of each group have

their greatest length in the same direction, two of said six sections occupying a square in the center of the cheese. The V-grooves are arranged directly opposite each other upon opposite sides of the cheese, and thereby forming upon the top and bottom sides of the cheese rectangular sections, identical in form and 35 number. There is also a half-circle groove B around each rectangular section, near its outer edge, upon the top side of the cheese, which forms smaller rectangular sections or name-plates for receiving any desired inscription. 40

The four edges of the cheese are plain and smooth.

Having thus described my said invention, what I claim as new, and desire to secure by 45 Letters Patent, is—

The design for a cheese as herein shown and described.

In testimony whereof I have signed my name in the presence of two subscribing witnesses.

NICHOLAS SIMON.
